UNITED STATES PATENT OFFICE.

NATHANIEL E. LOOMIS, OF ELIZABETH, NEW JERSEY, ASSIGNOR TO STANDARD OIL DEVELOPMENT COMPANY, A CORPORATION OF DELAWARE.

PREPARING HYDROCARBON PRODUCTS.

Application filed July 13, 1923. Serial No. 651,249.

This invention relates to the art of preparing hydrocarbon products, and will be fully understood from the following description.

Very light condensates from stills or from natural gas contain some constituents which are normally gaseous, and even in mixture are unstable and fugitive. Correspondingly, on exposure such constituents escape and in so doing also carry with them other heavier constituents which would otherwise be stable. This occasions considerable losses in the aggregate.

In accordance with the present invention, material of this character is blended with heavier naphtha in an absorber tower providing successive temperature zones and operating under pressure. One form of apparatus suitable for carrying out the invention is shown semi-diagrammatically in the accompanying drawing. In this tower A has a series of transverse partitions 1 upon which liquid may temporarily accumulate, but having perforations by which vapors may bubble up through. Along in the middle region of the tower is an inlet pipe 2; and at the top an outlet pipe 3 having a pressure-regulating valve 4. Another inlet pipe 5 at the top preferably ends in a spray head 6. A pipe 7 at the bottom of the tower serves as a draw-off for liquid. A suitable regulable cooling means is provided at the top of the tower, as for instance a coil 8 carrying a regulated cooling liquid.

The material containing unstable constituents, as for example a very light hydrocarbon stock, is introduced through pipe 2, while an absorbing medium such as heavy naphtha is also supplied by pipe 5 at the top of the tower. Such naphtha may vary in grade, but preferably is such that when the product is drawn off at outlet 7, a gasoline of finished or almost finished character results. The term heavy naphtha as used herein is intended to cover hydrocarbon oils generally that have a final boiling point not materially above that of gasoline and which may be blended with casing-head gasoline or

similar light condensates to form substantially finished gasoline with a balanced boiling range.

Pressure is maintained in the tower, varying somewhat in accordance with the particular hydrocarbons worked with, but in general being 100-300 lbs. per square inch. In order to insure that all the undesired gaseous constituents are stripped out heat is supplied to a suitable extent at the bottom of the tower by a coil 9 carrying a regulated flow of steam or other heating fluid. Other constituents also vaporizing in the tower are brought into thorough contact with the liquid, in progressively cooler zones proceeding toward the top and are blended and sorted until the constituents passing through outlet 3 are only such as are normally gases and not desired in gasoline. The liquid product desired is drawn off at the base by pipe 7.

The temperature in the still may be from about 260° to 300° F., the temperature of the vapors leaving the still ordinarily being a few degrees lower than the still temperature. The pressure usually falls progressively as the process continues. For example, a still showing an initial pressure of about 200 lbs. per sq. in. may show a pressure of about 100 lbs. per sq. in. after 16 hours running. The temperature and pressures will of course vary considerably with the particular stock being treated and the kind of naphtha used in washing.

What I claim is:

The improvement in the art of preparing hydrocarbon products, which comprises introducing a light condensate containing some hydrocarbons which are normally gaseous into the intermediate region of an absorber tower, and passing vaporizing constituents up through progressively cooler zones, while maintaining a pressure of 100-300 lbs. per square inch and supplying a flow of heavy naphtha countercurrently, and drawing off a substantially balanced gasoline from the bottom of the tower.

NATHANIEL E. LOOMIS.
